UNITED STATES PATENT OFFICE.

GEORGE N. HEIN, OF SAN FRANCISCO, CALIFORNIA.

HYPODERMIC SYRINGE WITH AMPULE-RECEIVING PISTON.

Application filed January 19, 1925. Serial No. 3,217.

To all whom it may concern:

Be it known that I, GEORGE N. HEIN, a citizen of the United States, residing at the city and county of San Francisco, and 5 State of California, have invented certain new and useful Improvements in Hypodermic Syringes with Ampule-Receiving Pistons, of which the following is a specification.

10 The present invention relates to improvements in hypodermic syringe constructions and more particularly to a form of device wherein a phial containing the medicament to be injected is adapted for reception with 15 in the piston of the syringe barrel and to be transferred into the syringe barrel on successive operations of the piston.

The invention has among its objects to provide a structure wherein the medicament 20 is not exposed to the atmosphere during its transfer from the phial to the syringe barrel, and is in this manner protected from contamination, and to provide a type of structure which is adapted for use in connection 25 with syringe barrels as universally constructed, with but the substitution of a different form of piston adapted for receiving the medicament containing phial.

With the above mentioned and other objects in view, the invention consists in the 30 novel construction and combination of parts hereinafter described, illustrated in the accompanying drawings and pointed out in the claims hereto appended; it being understood 35 that various changes in the form, proportion, size and minor details of construction within the scope of the claims may be resorted to without departing from the spirit or sacrificing any of the advantages of 40 the invention.

In the drawings disclosing the preferred embodiment of my invention—

Fig. 1 is a longitudinal sectional view of the assembled structure.

45 Fig. 2 is a view in elevation of the medicament containing phial.

In the drawings, wherein like characters of reference designate corresponding parts, 1 indicates a tubular syringe barrel, open at 50 its upper end as at 2, and from the opposite end of which extends a tapering tip 3 provided with a discharge bore 4.

55 Detachably fitted over the end of the tip 3 is a needle base 5 from which extends a conventional form of hypodermic needle 6. An elastic member 7 having a flexible check

valve portion 8 is carried by the tip 3, and the portion 8 prevents the passage of fluid inwardly through the bore 4, and at the same time admits of the passage of fluid outwardly through said bore. 60

Reciprocably mounted within the barrel 1, through its open end, is a tubular piston 9, open at its outer end, as at 10, and closed at its inner end, by the plug 11 threaded thereinto, the latter mounting an elastic hood 12, the periphery of which frictionally engages the inner wall of the barrel and forms a packing for the piston. The plug 11 is centrally bored, as at 13, and from the same extends inwardly into the piston 9 a needle 14. The hood 12 is slit inwardly as at 15 to provide a check valve flap 16, which precludes the passage of fluid inwardly through the bore 13 in the plug 12, and admits of the 75 passage of fluid outwardly therethrough.

An hermetically sealed phial 17, the open end 18 of which is closed by a cork or other puncturable sealing member 19, is inserted endwise, as in the drawing, into the piston, 80 through its open end 10, and longitudinal pressure is applied thereto, forcing the needle 14 to penetrate the closure 19 and extend into medicament 20, within the phial 17. 85

In the above description the operator assembles the parts, as in the drawing, and when using the device the operator grasps the end of the piston 20 and pulls the same outwardly. This action closes the check valve 8 and causes an unseating of the flap 90 16, and the created vacuum in the barrel 1, below the plug 11, withdraws the medicament from the phial 17 through the needle 14 and bore 13 into the barrel.

When the desired quantity of medicament 95 has been admitted into the barrel, inward pressure is applied to the piston, which causes a closing of the flap 16 and the opening of the check valve 8, resulting in the discharge of the medicament through the 100 needle 6.

It will be apparent that any desired quantity of medicament may be withdrawn from the phial 17 without exposing the remainder thereof to the atmosphere, and if 105 the proper closure is used in connection with the phial, the puncture therein may be automatically sealed on the withdrawal of the phial from the needle.

I claim:—

1. A hypodermic syringe including a barrel open at one end and provided with a

110

- hypodermic needle extending from its other end, a chambered piston reciprocably mounted therein and provided with a bore communicating with the interior of the barrel.
- 5 a tubular needle extending inwardly into the chamber of the piston and connecting with the bore, and a phial for reception within the piston chamber and provided with a puncturable closure for penetration by said
- 10 needle.
2. A hypodermic syringe including a barrel open at one end and provided with a hypodermic needle extending from its other end, an outwardly open valve controlling the discharge of fluid from the barrel through the needle, a chambered piston reciprocably mounted within the barrel and provided with a bore communicating with the interior of the barrel, a tubular needle ex-
- 15 tending inwardly into the piston and connecting with the bore, an outwardly opening
- 20 check valve controlling the passage of fluid

through the piston bore into the barrel, and a phial for being removably positioned within the piston and provided with a puncturable closure for penetration by said needle.

3. A piston for hypodermic syringes including a tubular body open at one end, a member for closing the other end, said member provided with an outlet channel and a flanged extension, a piston packing mounted on the flanged extension and cut inwardly to provide a check valve for controlling the fluid flow in one direction through said outlet channel, and a tubular needle carried by the closure member and extending inwardly into the tubular body with one end communicating with said outlet channel.

40 In testimony whereof I have signed my name to this specification.

GEORGE N. HEIN.
